FIG. 1

FIG. 2.

William Netzky

INVENTOR

UNITED STATES PATENT OFFICE

93,942

DESIGN FOR A BLOUSE

William Netzky, New York, N. Y.

Application October 3, 1934, Serial No. 53,464

Term of patent 3½ years

To all whom it may concern:

Be it known that I, WILLIAM NETZKY, a citizen of the United States of America, residing in Manhattan, county of New York and State of New York, have invented the new, original, and ornamental Design for a Blouse, of which the following is a specification, reference being had to the accompanying drawing, forming part thereof, wherein,

I claim:

The ornamental design for a blouse, substantially as shown.

WILLIAM NETZKY.
